(57) **CLAIM**

The ornamental design for a CCD camera, as shown and described.

DESCRIPTION

FIG. 1 is a side perspective view of an embodiment of a CCD camera according to the present design;

FIG. 2 is a front elevation view of the CCD camera of FIG. 1;

FIG. 3 is a right side elevation view of the CCD camera of FIG. 1;

FIG. 4 is a rear elevation view of the CCD camera of FIG. 1;

FIG. 5 is a left side elevation view of the CCD camera of FIG. 1;

FIG. 6 is a top plan view of the CCD camera of FIG. 1;

FIG. 7 is a bottom plan view of the CCD camera of FIG. 1;

and,
FIG. 8 is a right side elevation view of another embodiment of the CCD camera according to the present design and similar to FIG. 3 of the embodiment of FIG. 1 with broken away lines indicating the indeterminate length of the CCD camera. The rest of the views of the embodiment of FIG. 8 (FIGS. 1, 2, and 4-7) are otherwise the same as in the embodiment of FIG. 1.

The broken away lines of FIG. 8 do not indicate the specific length (beyond that shown in the drawings) and form no part of the claimed design.
